ALL METAL SEALING CAP FOR PAINT CONTAINERS

Filed April 21, 1930

UNITED STATES PATENT OFFICE

ANDREW WYZENBEEK, OF CHICAGO, ILLINOIS, ASSIGNOR TO BINKS MANUFACTURING CO., OF CHICAGO, ILLINOIS, A CORPORATION OF DELAWARE

ALL METAL SEALING CAP FOR PAINT CONTAINERS

Application filed April 21, 1930. Serial No. 446,038.

My invention relates to caps for liquid containers, and in some of its general objects aims to provide a metal cap which will effectively seal the container even when the pressure in the container is many times greater than the external pressure, without requiring the use of non-metallic sealing portions such as are likely to be affected by the liquid within the container.

Moreover, my invention aims to provide an entirely metallic container cap which can speedily and easily be attached to, and detached from, the receptacle portion of the container without the use of tools; which can easily be cleaned, and which will automatically adjust itself to considerable variations in the shape and size of interfitting parts of the cap and the container.

In its further objects, my invention aims to provide an easily manufactured and easily assembled container in which both the receptacle and the cap may be constructed entirely of metal, and in which the mouth portion of the receptacle (if made of light material) is effectively reinforced to withstand the expanding pressure exerted when the cap is attached to this mouth for sealing the container.

Still further and also more detailed objects will appear from the following specification and from the accompanying drawings, in which drawings

Fig. 1 is a fragmentary view of a liquid spraying appliance embodying my invention, including a receptacle portion, a cap member, and a part of a spray-gun; the lower portion of the spray-gun and the portion of the receptacle being shown in a section taken centrally and vertically of the receptacle, and the remaining portions of the spray-gun part being shown in side elevation.

Fig. 2 is a front elevation of the same portions.

Fig. 3 is an enlarged and fragmentary vertical section taken along the line 3-3 of Fig. 2.

Fig. 4 is a section taken along the line 4-4 of Fig. 2.

Fig. 5 is a fragmentary horizontal section,

taken along the line 5-5 of Fig. 2 and looking upward.

Fig. 6 is a plan view of the spray appliance portions shown in Fig. 1, drawn on a reduced scale and with portions of the cap of the container broken away.

In using socalled "paint-cup" spray appliances, such as the one here illustrated, the liquid when the high specific gravity must be forced out of the receptacle by air pressure; and with many of the now employed coating materials a considerable pressure is required for this purpose. Consequently, the cap of the container must be sealed to the receptacle with such effectiveness as to withstand this pressure, for which purpose it has heretofore been customary to interpose compressible seals between the cap and the mouth of the receptacle and the cap.

In practice, the materials commonly employed for these seals—such as leather or rubber—are gradually affected by many of the liquids used as coating materials, so that they occasionally need to be replaced. With some of the coating liquids now in use, this deterioration of the non-metallic seals by the liquid (and even by the fumes of the liquid) is so rapid that no material has been found sufficiently durable to withstand the action of the liquid for any considerable time, while also retaining the elasticity and compressibility needed for the effective sealing. Besides, such seals usually interfere with an expeditious cleaning of the container. Moreover, when such a seal crumbles or disintegrates as the result of the action of the liquid on the seal, portions of the seal may be forced up into the spray appliance along with the liquid, thereby clogging the appliance and interfering with its operation.

My present invention overcomes these difficulties by providing a container in which the entire cap, including the portion which affords the seal can be made of a metal which is not affected by the liquid, and by providing the receptacle and the cap with interfitting portions formed so that the needed compensation for any variations in their manufacture is afforded by a tapering of these

metal portions, thereby obviating the need of any compressible seal. Furthermore, my invention provides novel structural details both for the mouth end of the receptacle and for the cap, whereby the needed sealing effect and compensation for variations in the commercial manufacture of the parts can readily be secured, and whereby the pressure within the container may be utilized for insuring a large contact area between the receptacle and the sealing portion of the cap.

Illustrative of my invention, Fig. 1 shows the upper part of a metallic receptacle 1, which has its upwardly flaring mouth portion tightly gripped by a correspondingly formed stiffening ring 2, the extreme upper end portion 1 A of the container being spun outwardly over the upper edge of this stiffening ring. This stiffening ring is increased in rigidity by an integral horizontal flange 3 projecting outwardly from the lower end of the ring, and a plurality of uniformly spaced fingers 4 project radially of the ring from this flange, each of the fingers being slightly twisted out of the general plane of the flange in the same direction as shown in Fig. 2. To prevent the stiffening ring 2 from slipping downwardly, the receptacle desirably is bulged outwardly to present an annular shoulder 1 B underhanging the stiffening ring, which shoulder cooperates with the outwardly spun portion 1 A and the intervening mouth portion 1 C to form a groove in which the stiffening ring is seated.

35. Socketed in the upwardly flaring bore of the said container mouth portion 1 C is a correspondingly downwardly tapering sealing flange 5 which depends from and is integral with a cover lining 6. This cover lining has its central and major portion flat and in upward engagement with the flat and horizontal lower face of the central top portion 7 of a container top which extends radially beyond the mouth of the receptacle, and which container top has a flange 8 depending from its periphery. This flange 8 is desirably of somewhat larger bore than the outside diameters of the container mouth flange 1 A and the ring flange 3, and the top portion of the cover desirably includes an annular portion 9 disposed between the control top portion 7 and the depending flange 8, this annular top portion 9 being at a higher elevation than the said central top portion 7.

55. The cover lining desirably comprises a central portion 6 corresponding in diameter to the central cover top portion 7 and connected to the upper edge of the tubular sealing flange 5 by an annular portion 6 A which is raised above the top of the said lining portion 6, thereby affording a curved connection between the said lining and the sealing flange, as shown in Figs. 1 and 3. The central or main portion 6 of the cover lining is underhung by a flat stiffening disk 10 which de-

sirably is of somewhat larger diameter than the said portion 6, and which insures a rigid clamping of the cover lining to the central top portion 7 of the cover.

In the illustrated spray appliance, the cover top supports the body 11 of a spray gun, the interior of this body being connected to the interior of the receptacle by a liquid supply pipe 12 which is threaded into the said body and extends downwardly through the central cover top portion 7, the central lining portion 6 and the stiffening disk 10. Threaded on the liquid pipe 12 is a nut 17 which is run up against the stiffening disk to draw the gun body 11 tightly downward so against the top of the cover.

The gun body is further fastened to the cover by a hollow screw 13 which is threaded upward into an air supply passage 14 in the said body, and which screw has its head underhanging the stiffening disk 10, so that the lining and the stiffening disk are clamped to the cover by the same means which fasten the cover to the gun body 11.

With the top of the lining or sealing member thus rigidly clamped to the top of the cover by a stiffening disk, this entire lining or sealing member may be made of such thin metal (such as brass or bronze) that the pressure within the container will expand it against the mouth of the receptacle to insure a large contact area between the sealing flange 5 and the tapering mouth portion 1 C.

The depending flange 8 on the cover has suitably located portions thereof formed for interlocking with the fingers 4, which fingers are here shown as three in number. For this purpose, I am showing the said cover flange as provided with three counterpart slots 15 extending circumferentially of the flange, each such slot being considerably taller than the thickness of the fingers 4 and sloping upward in the same direction circumferentially of the cover. Adjacent to the lower end of each slot, the cover flange has a portion below the slot arched radially outward of the cover to afford an arched portion 16 of greater interior length than the width of one of the fingers 4 and to space the inner face of this arched portion farther from the axis of the cover than the outer end of such a finger, thereby permitting the arched portion to be slipped downward over the tip of the finger when the cover is rotated to align these parts.

When the cover is rotated (in a direction which would be counter-clockwise in Fig. 4 or Fig. 6) after the fingers have thus entered the lower ends of the respective slots, the lower edge of each slot is forced downward by its engagement with the correspondingly inclined lower face of the finger which projects through that slot, thereby pressing the cover downwardly. Consequently, the downwardly tapering tubular sealing portion of the cover is advanced spirally down-

ward within the similarly tapering mouth portion 1 A of the container to afford a seal of large area.

By using relatively soft metal—such as 5 aluminum—for the mouth of the container, and reinforcing this with a stiffening ring as above described, I permit the soft metal to yield sufficiently to insure an effective seal (even with air at high pressure within the 10 container), even when the bore of the container mouth does not correspond accurately in taper to that of the sealing flange on the cover lining. To enhance this adjusting of the interfitting parts to each other, I desirably 15 make the cover lining of a thin resilient metal (such as brass or bronze) which not only will afford the needed rigidity because of its resiliency and its tubular formation, but also will be sufficiently flexible to afford 20 the needed adjusting of the interfitting conical face portions to each other.

Owing to these provisions and also to the considerable width of the interengaging portions of the seal (or height in Figs. 1 and 3), 25 I can readily secure the desired effective sealing without employing any rubber, cork, felt or the like which would be affected by liquid or vapor within the container. In practice, the body of the attached spray gun affords 30 a convenient handle for rotating the cover in either direction, and the spiral movement of the cover not only permits both a tight sealing, but also facilitates the detaching of the cover in spite of such stickiness as may be due 35 to liquid or vapors within the receptacle.

So also, my use of a tapering annular seal engaging a tapering mouth portion enables me to secure a much larger contact area than can be obtained with the now common use of 40 a gasket engaging the upper end of the mouth of the receptacle, so that a relatively light clamping of the top member on the receptacle will suffice for securing an adequate sealing. Owing to the above described expanding of 45 the sealing flange 5 by the internal pressure, and also to the flexible connection of this flange to the cover, I do not require any high accuracy in the forming of this flange and in the forming of the tapering mouth end bore 50 of the container, so that I avoid expensive machining. Indeed, I have found small differences in the tapers of the two parts, or in their circular section to be immaterial, particularly if the taper of the sealing flange 55 is not less than that of the said mouth bore.

Moreover, the cover lining can easily be detached by merely loosening the nut 17 and the hollow screw 13, so that this lining can be 60 placed quickly and at low expense if necessary. So also, the space between the annular sealing flange 5 and the depending flange 8 of the cover permits the entire interior of the cover to be cleaned easily by dipping the 65 cover into a suitable solvent, which can be

done without detaching either the spray gun or the liquid tube from the cover.

However, while I have here illustrated and described my invention in an embodiment including a desirable arrangement of the means for latching the cover to the receptacle of the container, I do not wish to be limited to these or other details of the construction and arrangement thus disclosed, since changes 70 might obviously be made without departing 75 either from the spirit of my invention or from the appended claims.

Nor do I wish to be limited to the use of 80 my invention in connection with a container adapted to be held in the hand of the user, since its novel features will obviously be equally applicable to larger containers and containers designed for other purposes than their use in association with spray guns 85 mounted thereon.

I claim as my invention:

1. A container comprising an upright receptacle having the bore of its mouth end tapering downwardly, a cap lining including 90 a frustro-conical flange extending into and corresponding in taper to the taper of the said mouth end bore, a cap including a cap top extending above and across the upper end of the said flange and freely spaced from the upper end of the receptacle, a downwardly tapering stiffening ring housing and fitted upon the said mouth end of the receptacle, and co-operating means carried by the cap and the stiffening ring for forcing the said cap and lining downwardly with respect to the receptacle 95 when the cap is rotated in one direction with respect to the receptacle.

2. A container as per claim 1, in which the tapering mouth end portion and the said sealing flange are both of softer metal than the 100 stiffening ring.

3. A container as per claim 1 in which the disk-like top of the liner is connected to the said flange of the liner by a liner portion of 105 arcuate vertical section to permit a relative flexing of the said liner top and flange.

4. A container as per claim 1, in which the disk-like top of the liner includes a central liner portion integral with the said flange of the liner and bearing flatwise upwardly 110 against the cap top, in combination with a stiffening disk underhanging the said central liner portion, the stiffening disk being of more rigid material than the said central liner portion.

5. In a container, an upright receptacle including a metallic mouth end of downwardly tapering frustro-conical tubular form; a cap member comprising an inverted cup-shaped 115 cap and inner inverted cup-shaped metallic liner; the liner having a downwardly tapering tubular flange entering and fitting the bore of the said mouth end, and also including a top disk underhanging and fastened to 120 the top of the said cap; and means operatively 125

interposed between the cap top and the receptacle for forcing the cap top downwardly so as to wedge the tubular flange of the cap liner in the bore of the mouth end of the receptacle.

5 6. A container as per claim 5, including a stiffening ring housing the mouth end of the receptacle to prevent expansion of the said mouth end by the downward forcing of the said tubular flange into the said mouth end.

10 7. A container as per claim 5, including a stiffening ring housing the mouth end of the receptacle to prevent expansion of the said mouth end by the downward forcing of the said tubular flange into the said mouth end, the receptacle having a shoulder underhanging the stiffening ring to prevent the said ring from sliding downwardly.

15 8. A container as per claim 5, including a stiffening ring housing the mouth end of the receptacle to prevent expansion of the said mouth end by the downward forcing of the said tubular flange into the said mouth end, the receptacle having its extreme mouth end portion spun outwardly over the upper end of the stiffening ring.

20 9. A container as per claim 5, including a stiffening ring housing the mouth end of the receptacle, the stiffening ring being of less ductility than the said mouth end of the receptacle.

25 10. A container as per claim 5, including a stiffening ring housing the mouth end of the receptacle, the said receptacle mouth end having shoulders respectively overhanging and underhanging the stiffening ring to prevent vertical movement of the said ring in either direction with respect to the receptacle.

30 11. A container comprising an upright receptacle having the bore of its mouth end tapering downwardly, a cap liner including in integral formation a disk-like top and a frusto-conical tubular flange depending from the outer edge of the said top and corresponding in taper to the taper of the said mouth-end bore, a cap including a cap top extending above and across the said top on the liner and freely spaced from the upper end of the receptacle; and cooperating means on the receptacle and the cap for forcing the said cap downwardly with respect to the receptacle so as to wedge the said flange of the cap liner in the mouth end of the receptacle, the disk-like top of the liner including a central liner portion integral with the said flange of the liner and bearing flatwise upwardly against the cap top, in combination with a stiffening disk underhanging the said central liner portion, the part of the disk-like liner top radially outward of the said central liner portion being offset upwardly from the latter portion so as to dispose the bottom of that part higher than the top of the stiffening disk.

Signed at Chicago, Illinois, April 18th, 1930.

65 ANDREW WYZENBEEK.
